UNITED STATES PATENT OFFICE.

HENRY E. LORENTZ, OF WASHINGTON, DISTRICT OF COLUMBIA.

KEY-LOCKING DEVICE.

Application filed December 8, 1921. Serial No. 520,924.

To all whom it may concern:

Be it known that I, HENRY E. LORENTZ, citizen of the United States, residing at Washington, District of Columbia, have invented certain new and useful Improvements in Key-Locking Devices, of which the following is a specification.

This invention relates to a simple device for preventing the removal of a key from its lock, from the outside of the door by an unauthorized person, and is particularly applicable to the conventional type of door key.

The principal object of the invention is to provide an adequate and efficient means of maintaining the key within the lock, so that said key can be secured therein from the inside, and the key-locking means so engaged with the shank of the door knob, as to make it impossible, from the outside to either remove said key or its retaining means.

Another object is to construct the device so that it will accommodate itself to most any size key and lock, and at all times, when in operative position, snugly embrace the shank of the door knob regardless of the size thereof within reasonable limits.

A further object of the invention is the provision of a device of this character, simple in construction and operation, and one that can be manufactured to sell at a minimum cost.

The preferred embodiment of the invention is illustrated in the accompanying drawings, in which—

Fig. 1 illustrates the device in operative position and the manner of removing the same.

Fig. 2 is a side view thereof.

Fig. 3 shows the manner of applying the device.

Fig. 4 illustrates a modified construction thereof.

Referring to the drawings in details, the improved device is preferably constructed of a single piece of wire, bent to produce an upper eye or loop, 1, said loop being formed nearer one end of the wire than the other, resulting in a long and short leg extending from said loop. In the preferred construction the legs are crossed at the base of the loop and beginning at this point of intersection said legs are bent in reverse curves 2 and 3, toward each other, forming jointly substantially an open ring, adapted to embrace the shank, 4, of the conventional

type of door knob, the longer leg, however, forming the greater portion of said ring. The shorter leg is then bent sharply in the reverse direction at substantially a right angle, leaving a straight outwardly and downwardly extended portion, 5, for the purpose of manipulation, as will hereinafter appear from the operation of the device. The longer leg beginning at the ring is bent straight downwardly for a relatively longer distance, as at 6, and then bent sharply upwardly as at 7, forming a V shaped spring like member adapted to be inserted through the handle of the key, 8, as will be noted upon referring to the various figures of the drawing.

In the modification as illustrated in Fig. 4, the legs are not crossed as previously described but merely meet at the base of the loop and from there bent in a manner similar to the preferred construction.

From the foregoing description, the operation of the device, it is believed, will be perfectly obvious. Assuming that the door has been locked and the key turned, and it is desirous to secure the key in this position, the lower tapered end of the device is inserted through the handle of the key, and simultaneously therewith the short extension, 5, and the downward extension, 6, are pressed into engagement with the shank 4, of the door knob. A continued pressure in this direction will open the ring formed by the inwardly curved portions 2 and 3, until the same pass over and completely embraces said shank, the above described operation being clearly illustrated in Fig. 3. Owing to the peculiar construction of the two-part shank engaging ring and the tapered spring like key engaging portion of the device, the same will conveniently adapt itself to various sizes of keys and locks, which is a very important and desirable feature in devices of this character. In addition by reason of the spring like ring, and the opening thereof being substantially on the side, the device will at all times when in operative position be securely clamped to the shank of the door knob, and any upward movement thereof for displacing the same will be prevented.

To remove the device from the door knob and key, it is only necessary to exert an upward pressure on the extension 5, (Fig. 1), to open the shank embracing ring and subsequently force the device to one side to clear the door knob, whereupon the tapered

key engaging portion can be readily removed from the key.

What I claim is:

1. A key retaining device comprising a resilient open ring portion normally closed and a downwardly extending key engaging portion, and means for expanding said ring portion to snap over and embrace the shank of a door knob, following the insertion of the key engaging portion within the handle of the key.
2. A key retaining device, comprising a resilient ring portion adapted to open on the side, but normally closed, and a downwardly extending key engaging portion, and means for expanding said ring portion to snap over and embrace the shank of a door knob, following the insertion of the key engaging portion within the handle of the key, said ring extending around and beneath said shank to prevent the upward movement of said device.
3. A key retaining device, comprising a resilient open ring portion and a pair of diverging legs extending from said open ring, between which the shank of a door knob is wedged for opening said ring during the application of the device, one of said legs being longer than the other and extending downwardly in a position to be inserted into the handle of the key.
4. A key retaining device comprising an

upper closed handle portion, an intermediate expandible and contractable circular door knob shank-embracing portion, and a resiliently adjustable downwardly extending key engaging portion.

5. A key retaining device constructed of spring wire, comprising an upper bent closed handle portion, an intermediate resilient open ring portion and a resiliently adjustable downwardly extending key engaging portion.

6. A key retaining device constructed of spring wire, comprising an upper loop or handle portion, an intermediate resilient open ring portion adapted to snap over and embrace the shank of a door knob, the opening in said ring being to one side of the vertical axis of the device, an outwardly and downwardly projecting short leg extending from said ring adjacent the open side thereof and a relatively long, downwardly projecting leg forming another extension of said ring from the other side of said opening, between which legs the shank of a door knob is wedged for opening said ring during the application of the device, said long leg being again bent upwardly to form a V shaped resiliently adjustable portion adapted to be inserted in the handling of the key.

In testimony whereof I affix my signature.

HENRY E. LORENTZ.
